UNITED STATES PATENT OFFICE.

JOSEPH R. NAVARRE, OF LAKESIDE, WASHINGTON.

SAFETY DEVICE FOR AVIATORS.

1,349,782.

Specification of Letters Patent. Patented Aug. 17, 1920.

Application filed February 21, 1919. Serial No. 278,542.

To all whom it may concern:

Be it known that I, JOSEPH R. NAVARRE, a citizen of the United States, residing at Lakeside, county of Chelan, and State of Washington, have invented certain new and useful Improvements in Safety Devices for Aviators, of which the following is a specification.

My invention relates to safety devices 10 for aviators and particularly to improvements in life-saving apparatus in the nature of a parachute to be used in case of accident.

The object of my invention is to provide 15 a device of the character mentioned which may be readily attached to the aviator and which may be quickly thrown into operation in case of accident. A further object of my invention is to provide a device as 20 mentioned which shall be in no way connected to the aeroplane and which shall be of such construction and arrangement that it will not interfere with the aviator leaving the machine. A further object of my 25 invention is to provide a device as mentioned which, when in inoperative position, will serve as additional protection for the head of the aviator. Other objects will appear hereinafter.

With these objects in view my invention 30 consists generally in a parachute adapted to be folded into small space upon the top of the head, and means for attaching the same to the body. My invention 35 further consists in a device as mentioned in which the attaching means comprises a body harness and connecting straps. My invention further consists in a device as mentioned in which the connecting straps are 40 detachably connected to the hood of the aviator so as to prevent the same from normally hanging loose. My invention further consists in a safety device of the class mentioned comprising a parachute adapted to 45 be folded into small compass, and means for attaching the same to the aviator together with means normally tending to extend the parachute into operative position and readily releasable means for holding 50 the latter normally out of operation. My invention further consists in a device as mentioned comprising a helmet, a parachute attached to said helmet and adapted to be folded thereon, a body harness and 55 a connection between the body harness and the helmet. My invention further consists

in various details of construction and arrangements of parts all as will be fully described hereinafter and particularly pointed out in the claims.

My invention will be more readily understood by a reference to the accompanying drawings forming a part of this specification and in which—

Fig. 1 is a perspective view of the device in folded or inoperative position, illustrating the same in conjunction with the hood and adjacent parts of the aviator's costume.

Fig. 2 is a vertical transverse section of 65 the device exclusive of the harness or attaching means and illustrated upon an enlarged scale.

Fig. 3 is an elevation of the device in 70 operative position.

Fig. 4 is a detail perspective view of 75 the means for extending the parachute.

Fig. 5 is a detail sectional view on the line $x-x$ of Fig. 4.

Fig. 6 is a detail perspective view of 80 a portion of the locking device.

Fig. 7 is a detail sectional view illustrating one manner of connecting the parachute and the harness to the helmet,

Fig. 8 is a perspective view illustrating 85 a slightly modified form of connecting means.

Fig. 9 shows a modified arrangement.

Referring now to the drawings, 1 indicates broadly the hood and adjacent portions of the costume of an aviator which is shown conventionally only, as the form of this portion of the device has nothing to do with my invention except in so far as it is provided with means for attaching certain straps thereto as will be more fully described hereinafter. 2 indicates the helmet which is preferably formed of aluminum on account of both strength and light weight, and comprises a comparatively low 90 crown 3 and preferably straight brim 4. The crown is lined with a comparatively thick layer 5 of felt which will absorb in a great measure any shock received upon the helmet.

Secured to the helmet 2 by a plurality of cords 6 is a parachute 7, preferably made of thin strong silk fabric. The parachute is of ample size when expanded to serve the normal purpose of a parachute, and is provided adjacent its periphery with an annular casing 8 in which is arranged a flexible

spring band 9. The spring band 9 is adapted to be coiled within the casing, as illustrated in Figs. 2 and 4, to fit upon the brim 4 of the helmet, and is provided with 5 suitable means for holding the same in coiled position until released by the aviator when it is desired to throw the parachute into operation. The locking means comprises an aperture 10 adjacent one end of 10 the band and an eye or loop 11 formed on the band substantially one convolution of the spring from its end when in coiled position to extend through said aperture, as shown clearly in Figs. 4, 5 and 6. After 15 the coiled device is placed in position on the brim a locking pin 12 is extended vertically through an aperture 14 in the brim 4, and the eye 11.

To fold the parachute upon the helmet, 20 the spring 9 is first coiled into the position shown in Fig. 4 with the eye 11 extending through the aperture 10. The cords 6 are then laid upon the brim 4 of the helmet and the periphery of the parachute with the in- 25 closed spring 9 resting upon the brim where it is held in position by a plurality of upwardly projecting spring tongues 15, the resiliency of these springs being but sufficient to hold the device in position while 30 the spring 9 is locked; and then the pin 12 is projected through the aperture 14 and eye 11. Then the parachute *per se* is laid in the folds upon the crown of the helmet. See Fig. 2.

35 To hold the folded parachute upon the crown of the helmet and to protect the same from the weather, a waterproof cover 16 is provided, preferably of rubber and equipped with a coiled spring expanding 40 device 17 similar to the spring 9, but not necessarily so long, as the sole purpose of this spring is to hold the device in position when folded and to free the device of the cover when released. This is arranged in 45 a hem or casing 18 on the edge of the cover 16 and has the same aperture and eye fastening 10' and 11' as has the spring 9. This device is also held in position by the spring tongues 15.

50 To secure the device to the aviator, a body harness is provided comprising a pair of shoulder straps 20 adapted to extend under the arms, a back strap 21, and a breast strap 22 provided with a buckle 23 55 for fastening the same in position. Secured to the shoulder straps 20 are connecting straps 24, the upper ends of which are attached to the brim 4 of the helmet by being looped through apertures 25 therein.

60 If desired, a reinforcing plate 26 may be provided extending through a strap and resting upon the brim 4. The straps 24 are equipped with parts of glove fasteners 27, the coöperating parts thereof 28 being ar- 65 ranged upon the sides, neck and shoulder of

the helmet 1, as indicated in Fig. 3. These fasteners serve as means to hold the straps 24 so as to avoid the same hanging loose under normal conditions.

The operation of the device is as follows: 70 After the parachute and its cover have been placed in position upon the helmet as above described, the helmet is placed upon the head over the hood 1 and the body harness secured in position. The straps 24 are 75 then secured in position by means of the glove fasteners 27, 28. Should an accident occur necessitating the aviator leaving the machine, he may throw the device into operation by merely pulling the locking pin 80 14. This releases both the spring 17 of the cover 16 and the spring 9 of the parachute. The first-mentioned spring by expanding 85 disengages itself from the spring tongues 14 and throws the cover free from the parachute. The spring 9 frees the device from the spring tongues 15 and fully expands the periphery of the parachute so that the same will quickly fill with air. The weight 90 of the body disconnects the fasteners 27 and 28 and allows the straps 24 to straighten, thereby raising the helmet a few inches from the head, as shown clearly in Fig. 3.

It is obvious that with a device of the character mentioned the aviator may quickly 95 leave the machine and not be encumbered with any bulky safety device attached to or stored within the plane. It is also obvious that the device when folded into inoperative position is of small size, entirely out 100 of the way of the operator, and serves as additional protection for the head.

I claim:—

1. A safety device for aviators comprising a helmet, a parachute, a coiled spring in the 105 periphery thereof, said spring having an aperture adjacent one end thereof, an eye on said spring adapted to extend through said aperture to hold the spring in coiled position, a releasing pin extending through 110 said eye, substantially as described.

2. A device as set forth in claim 1, in combination with a casing adapted to hold said parachute in folded position upon said helmet, substantially as described.

3. A device as set forth in claim 2 further characterized by a releasing spring within said casing, substantially as described.

4. A device as set forth in claim 3 in which the spring in the casing is similar to 120 the spring in the parachute and in which the said releasing pin releases both springs, substantially as described.

5. A safety device for aviators comprising a helmet having a crown and a brim, a parachute, a coiled spring in the periphery thereof, means for normally maintaining said spring in coiled position upon said brim, manually operable means extending through said brim for releasing the same, and means 125 130

for attaching the parachute to the aviator, substantially as described.

6. A safety device for aviators comprising a parachute, means for holding the same in folded position upon the head, a body harness, straps interposed between said harness and said parachute, a hood, and detachable coöperating fasteners on said straps and said hood, substantially as described.

10 7. A safety device for aviators comprising a helmet consisting of a crown and brim, a parachute adapted to be folded upon said helmet, cords connecting said parachute and said helmet, an expansible coiled spring ar-

ranged adjacent the periphery of said parachute, manually operable means locking the same in coiled position, resilient means on said brim for holding the coiled spring in position thereon, and means for attaching the helmet to the aviator, substantially as described.

In testimony whereof I have signed my name to this specification in the presence of two subscribing witnesses.

JOSEPH R. NAVARRE.
